UNITED STATES PATENT OFFICE.

ARTHUR G. WILLARD, OF BAKERSFIELD, CALIFORNIA, ASSIGNOR TO BAKERSFIELD IRON WORKS, A CORPORATION OF CALIFORNIA.

PUMP FOR OIL-WELLS.

No. 885,899.

Specification of Letters Patent.

Patented April 28, 1908.

Application filed May 8, 1905. Serial No. 259,257.

To all whom it may concern:

Be it known that I, ARTHUR G. WILLARD, a citizen of the United States of America, residing at Bakersfield, in the county of Kern and State of California, have invented certain Improvements in Pumps for Oil-WellS, of which the following is a specification.

Heretofore the pumping of oil wells in southern California has involved great difficulty and expense by reason of the presence in the wells, in combination with heavy asphaltum oils, of water and sand carried thereby, the latter causing the rapid wearing away of valve seats and valves; some of the sand being of so fine a nature that it finds its way between the working barrel and the plunger, thus rapidly wearing away the same, and making the pump useless. In order to avoid this wearing away of the plunger and barrel 10 it is necessary to provide at the upper portion of the working barrel a packing around the plunger through which the plunger may work and which will exclude sand from between the plunger and the working barrel. 20 A further difficulty arises, however, which has heretofore prevented the use of any known packing around the plunger, and through which the plunger would work, which would thus exclude the sand from the 25 working barrel; that is to say, the sand accumulates sometimes with great rapidity above the standing valve, thus necessitating frequent withdrawals of the plunger and the standing valve to a position in the pump 30 where the oil above the same can rush downward to flush out such accumulations, and with the packing heretofore known it has been found impossible to return the plunger to the working barrel, for the reason that 35 the downward rush of oil and accumulations displaces the packing, so that before the pump can again be operated the tubing and working barrel must be withdrawn in order to 40 reinsert the plunger in the working barrel, and repack the same.

An object of my invention is to provide an oil-well pump which avoids the difficulties and expense above referred to.

A further object of the invention is to provide a new construction of working barrel for oil-well pumps, whereby the working barrel can be packed and assembled ready for the field independently of the plunger and the well tubing, and can be shipped to the field 50 and can there be installed by the workmen,

and after being placed in the well can be fitted with the plunger without inconvenience or loss of time, by simply running the plunger down the tubing, through the packing and into the working barrel. The construction 60 of plunger and standing valve adapted for this purpose is common, and may be understood by reference to the patent to Frank A. Garbutt, Number 586,707, dated July 20, 1897.

My invention comprises a working barrel 65 for an oil-well pump, having two elongated bores of different diameters, the larger being topmost; a plunger in said bores, metallic rings in the larger of said bores, and means 70 operable by the pressure of the liquid above said rings to temporarily contract said metallic rings against the plunger so long as sufficient liquid is above said rings. The construction by which this is accomplished 75 consists in split metallic rings that are cone-shaped at their ends, and another ring or rings subject to the pressure exerted by the liquid, having flaring ends to fit on the conical ends of the split rings, all of such rings 80 being freely movable in said larger bore, so that when the pressure of the liquid comes upon the uppermost ring the several split rings are compressed to tightly fit the plunger, thus excluding the sand from the straight 85 elongated tubular portion of the barrel in which the plunger works.

In order to make the barrel adaptable for 90 assemblage at the machine shop, thence to be shipped to the field, screwed onto the tubing and inserted into the well, and to allow the standing-valve and plunger to then be inserted through the same, the upper ring 95 which is to receive the pressure of the liquid, is made flaring upwardly, and the enlarged portion of the working barrel is internally 100 grooved, and a resilient ring is inserted into the groove after the packing rings have been placed, all of which will hereinafter appear more fully.

The invention consists further in the constructions and combinations of parts herein-after described and particularly pointed out in the claims, and will be more readily understood by reference to the accompanying 105 drawings forming part of this specification, and in which

Figure 1 is a vertical, sectional view of the pump embodying my invention. Fig. 2 is a vertical, sectional view showing the same in- 110

side a well casing, the plunger of the pump and the metallic packing rings and valve cages being shown in elevation. Fig. 3 is a perspective view of the retaining device for holding the metallic packing rings in position. Fig. 4 is a perspective view of one of the solid metallic packing rings. Fig. 5 is a perspective view of one of the split metallic packing rings.

10 A valuable part of this invention is the new form of working-barrel which comprises two screw-threaded connections *a*, *b*, forming the ends of the working-barrel, a main portion *c*, and an enlarged portion 7, a slanting shoulder 8 being between these two portions for the purpose hereinafter to be explained, and an annular seat *d* being provided at the top of the enlarged portion 7 for the purpose hereinafter to be explained. 15 20 An advantage gained by constructing the barrel in this way is that provision may be made for a stroke of the plunger much longer than the length of the working-barrel, by simply connecting to the lower end of the barrel a section of pipe 4 to hold the standing valve 5; it only being necessary in actual practice to bore out the working-barrel, and this may readily be renewed from time to time without the necessity of renewing the other parts which are connected thereto. 25 30 That is to say, in actual practice, the connection 4 does not have to be bored out, and it is not subject to wear, but it is desirable that the plunger of the pump shall run down into the same, thus giving the length of stroke required. By the novel construction of barrel herein set forth, I make provision whereby the necessary working fit on the plunger can be insured at the least expense 35 40 and inconvenience.

As shown in the drawings, 2 is a well casing, and 3 the working barrel of the pump which, as shown, is connected at its bottom with the section 4 in which is mounted the standing valve 5 of the ordinary or any preferred construction. Below the standing valve is an ordinary perforated pipe 6 for the inlet of oil to the interior of the working barrel. The upper end of the working barrel 3 is of greater diameter than the main portion of the working barrel, and the interior surface, where the enlarged upper portion 7 merges into the main working barrel 3, is inclined so as to provide a seat 8 for the lower metallic packing ring.

55 Mounted on the seat 8 inside the expanded portion 7 of the working barrel, is a metallic packing ring 9. In the drawings, this packing ring is shown as split and having a beveled lower edge 10, the bevel of the lower edge 10 corresponding to the inclination of the seat 8.

11 represents an integral metallic packing ring, the lower edge of which is inwardly beveled as at 12 to correspond with the bevel 60 of the upper edge of the split ring 9, so that

the ring 11 seats on the ring 9, and the exertion of pressure on the ring 11 tends to close the split ring 9. There may be any suitable number of alternate rings 9, 11. In the drawings I have shown three pairs of such rings. 75 At the upper end of the enlarged portion 7 of the working barrel, I provide an annular groove or channel in which is seated a split retaining ring 13, by means of which the packing rings are held from movement with 75 the pump plunger. Owing to the retaining ring 13 being above the uppermost packing ring, said retaining ring may be easily inserted into the groove after the packing rings are all in place.

80 14 represents the sucker rod which extends up through the casing, and is connected with the walking beam or other reciprocating means, not shown. The lower end of the sucker rod 14 is connected with the valve 85 cage 15, which may be of the ordinary or any preferred construction. This valve cage is in turn connected in the usual manner with the pump plunger 16. This plunger extends through the packing rings 9, 11, and through 90 the working barrel 3, there being a close working fit between the outer surface of the plunger 16 and the interior of the working barrel 3. 17, 17' represent ball valves of the ordinary or any preferred construction. 95

As shown most clearly in Fig. 5, the rings 9 are preferably split by a split or cut extending inwardly from each end, the longitudinal cuts thus formed overlapping and being connected near the middle portion of the overlap by a horizontal portion of the cut. This construction provides pockets 18 in which any sand or solid matter may collect, thereby preventing the crossing of such sand or solid matter through the horizontal portion of the 105 cut over to the lower longitudinal cut, and thence down in between the solid rings and the plunger, as might occur when the solid rings have been long in use, as said solid rings do not contract to take up the wear. 110 The horizontal portion of the cut or split in the split rings will remain open unless uneven pressure is applied to the end of the ring. In such case the horizontal part of the split may close up, the opposite walls 115 thereof abutting against each other so as to prevent the ring from being twisted out of shape, which might occur if the split did not have a horizontally-extending portion.

19 designates the tubing of the pump, the 120 same being screwed into the enlarged portion 7 of the working barrel. By reason of the uppermost solid ring 11 being beveled at the top along its inner edge an open space 20 is provided above said uppermost solid ring 125 11 and communicating with the interior of the tubing below the plunger valve 15, whereby the weight of the liquid in the tubing will be applied directly to the uppermost ring and cause the split rings to be com- 130

pressed upon the plunger. The retaining ring 13 forms a convenient means for stopping the packing rings from being drawn up by friction of the plunger, but I do not limit myself to the exact construction shown in any of the views.

By providing the alternate split and solid metallic packing rings 9 and 11, and providing the upper edge of the split rings with a bevel over which the lower edges of the solid rings fit, the weight of the fluid on the top metallic ring causes the solid metallic ring or rings to bear down upon the split ring or rings and to close the split ring or rings about the plunger, and to maintain a close working fit between the outer surface of the plunger and the interior of the split rings; thus automatically taking up any looseness therebetween, effectually preventing any sand and water working between the split rings and the surface of the plunger.

Pumps of this style have been in actual use in wells, and have demonstrated that by thus constructing the pump, the life of the working barrel and plunger is many times increased.

In considering this invention with relation to packing rings used in steam engines, it is to be noted that there is a difference in the character of the devices and of the work to be performed. That the metallic packing rings I have shown for a deep well pump depend entirely upon the weight of the fluid for closing the rings around the plunger, and that the metallic rings used in steam engines and steam pumps necessarily require a gland to compress such rings around the piston rod by the aid of studs or bolts. Such studs or bolts, or like means cannot be employed, for this purpose in deep well pumps.

This invention includes the several parts and combinations of parts by which the purposes of my invention are attained.

Having thus described my invention, I claim as new and desire to secure by Letters Patent:—

1. An oil pump comprising a working barrel, a hollow plunger therein, a sucker rod connected with the said plunger, a standing valve and cage, a valve and cage at the upper end of said plunger, alternate split and solid packing rings upon said plunger at the upper end of said working barrel, said split rings having their upper edges beveled, and said solid rings having inwardly-tapering sockets in their lower ends and adapted to fit over and compress said split rings, a portion of the split extending horizontally of the split rings and leaving a pocket at the end of a longitudinal portion of the split, and means for holding said packing rings in fixed relation to said working barrel.

2. An oil pump comprising a working barrel having an expanded upper portion, alternate split and solid metallic packing

rings mounted in said expanded portion, the solid rings fitting over and embracing the upper edges of the split rings and adapted when pressure is applied to the rings to cause the split rings to contract, a plunger working through said rings and working barrel, valve cages, a sucker rod, means for holding said packing rings in fixed relation to said working barrel, said split rings having pockets for preventing solid matter passing through the split portion of said split rings.

3. A pump provided with a split packing ring, and means for causing said ring to contract, the split in said ring comprising longitudinal cuts connected by a horizontal cut, said horizontal cut being arranged with relation to a longitudinal cut to leave a pocket at the end of said longitudinal cut.

4. A deep well oil pump comprising a working barrel and plunger, elastic and inelastic packing rings alternately arranged in said barrel, the inelastic rings being above and tending to compress the elastic rings around the plunger, and elastic means at the top for retaining said rings.

5. A pump provided with a split packing ring, the split in said ring comprising longitudinal cuts connected by a horizontal cut, said horizontal cut being arranged with relation to a longitudinal cut to leave a pocket at the end of said longitudinal cut.

6. A pump comprising upright tubing; a working barrel fastened to the tubing and provided below the tubing with an enlarged portion; a standing valve, a valved hollow plunger in the working barrel above the standing valve; packing rings around the plunger in the enlarged portion of the barrel, the uppermost ring being solid and other rings being split and tapered for compression on the plunger, a portion of the split extending horizontally of the rings leaving an opening at the end of the longitudinal portion of the split, an open space being provided above the uppermost solid ring, the same communicating with the interior of the tubing below the plunger valve whereby the weight of liquid in the tubing will cause the split rings to be compressed upon the plunger.

7. A deep well oil pump comprising upright tubing; a working barrel fastened to the tubing and provided below the tubing with an enlarged portion; a standing valve, a valved hollow plunger in the working barrel above the standing valve, packing rings around the plunger in the enlarged portion of the barrel, means for holding said packing rings in fixed relation to said working barrel, the uppermost ring being solid and other rings being split and tapered for compression on the plunger, an open space being provided above the uppermost solid ring, the same communicating with the interior of the tubing below the plunger-valve, and a stop above said ring to prevent the same from

being drawn upward by the friction of the plunger.

8. In a deep well oil pump provided with a sand excluder, the combination of a barrel, a plurality of plunger encircling members therein having slots and compressible in the direction of said slots, said members being alternately spaced by a plurality of solid rings arranged above the compressible members respectively, said solid rings and compressible members being provided with corresponding bevel faces whereby to snugly engage each other, means for retaining said rings in position, the upper end of the uppermost of said rings being free in the open barrel of the pump to receive the pressure of the liquid from the same, and a plunger in said barrel extending through the packing rings to produce a vacuum therebelow.
10. 9. A set of metallic packing rings for deep well pumps, or working barrels; the set to consist of two or more rings, one or more of said rings being split; means for compressing the split rings tightly about the plunger by utilizing the downward pressure of the liquid in the tubing.
10. A pump, or working-barrel having a tubular plunger, and provided with a set of packing rings at the upper end of said pump or working-barrel; the barrel being counter-bored from the upper end to admit the rings; a portion of said rings being split to enable them to contract; said rings so arranged by means of concaved and convexed ends that by utilizing the weight of the fluid in the tubing resting on the upper ring, the split rings compress tightly about the plunger.
11. A pump, or working-barrel; a tubular plunger; the usual valve at the upper end of the plunger, and at the lower end of the pump; a set of metallic packing rings; means for holding the rings in place; means for compressing the rings about the plunger by utilizing the pressure, or weight of liquid in the tubing, thereby preventing the usual wear or cutting of pump by sand.
12. A working barrel for an oil-well pump having two elongated bores of different diameters with a bevel shoulder sloping downward between the same, an internal annular groove near the top of the larger bore, a plurality of metallic packing rings slidable in said larger bore, a ring in said groove to retain said packing rings and means operable by the pressure of liquid in the top of said larger bore to temporarily contract the rings.

13. A working barrel for an oil-well pump having two elongated bores of different diameters, the larger being top-most, a plunger in said bores, metallic rings in the larger of said bores, and means operable by the pressure of the liquid to temporarily contract said metallic rings against the plunger.

14. A deep well oil pump provided with a sand excluder consisting of a plurality of plunger-encircling members having slots and compressible in the direction of said slots, said members being alternately spaced by a plurality of solid rings, arranged above the compressible members, respectively, said solid rings and compressible members being provided with corresponding beveled faces whereby to snugly engage each other, the upper end of the uppermost of said rings being free in the open barrel of the pump to receive the pressure of the liquid from the same, and a plunger in said barrel extending through the packing rings to produce a vacuum therebelow.

15. A deep well oil pump and sand excluder therefor comprising in combination, a barrel, a plurality of plunger encircling members therein having slots and compressible in the direction of said slots, said members being alternately spaced by a plurality of solid rings arranged above the compressible members respectively, said solid rings and compressible members being provided with corresponding beveled faces whereby to snugly engage each other, and means for retaining said rings in position, the upper end of the uppermost of said rings being free in the open barrel of the pump to receive the pressure of the liquid from the same, and a plunger in said barrel extending through the packing rings.

16. A working barrel having two elongated bores of different diameters and terminating at its ends in screw-threaded portions, and provided near the top of the larger bore with an internal annular groove, tapered split packing rings in said larger bore, a ring on top of said split packing rings to cause the same to contract when pressure is applied to said ring, and an elastic ring in said groove.

In testimony whereof, I have hereunto set my hand at Los Angeles, California, this 29th day of April, 1905.

ARTHUR G. WILLARD.

In presence of

FREDERICK S. LYON,
JULIA TOWNSEND.
